UNITED STATES PATENT OF 'ICE.

DIMITRY BALACHOWSKY AND PHILIPPE CAIRE, OF NEUILLY-SUR-SEINE, FRANCE.

DYNAMO-ELECTRIC MACHINE.

1,133,834.

Specification of Letters Patent. Patented Mar. 30, 1915.

Application filed June 16, 1909. Serial No. 502,441.

To all whom it may concern:

Be it known that we, DIMITRY BALACHOWSKY and PHILIPPE CAIRE, both residents of Neuilly-sur-Seine, Seine, France, the former a subject of the Emperor of Russia, the latter a citizen of the Republic of France, have invented new and useful Improvements in Dynamo-Electric Machines, which improvements are fully set forth in the following specification.

The object of the present invention is to provide means for the automatic regulation of direct-current electric machines. Such regulation has heretofore been commonly attained by compound winding. This however does not give a sufficiently close regulation for all purposes, and the range of regulation is undesirably limited.

The invention consists in the combination, with the armature and field of the machine, of means controlled by the shifting of the neutral line due to armature reaction, for varying the strength of the field. Such means may comprise two brushes of like sign both situated in the same zone of commutation, said brushes being connected to a specially designed auxiliary field coil.

In the accompanying drawing, Figure 1 shows conventionally a bipolar generator to which the invention is applied, and Fig. 2 a bipolar generator provided with the invention as shown in Fig. 1, and with means specially useful in starting the machine.

Similar letters of reference indicate corresponding parts in the figures.

Referring to the drawings, the armature 10 is mounted to rotate in the usual manner between the poles 11 and 12 of the field, and is provided with a commutator 13, from which the current generated is taken by brushes *k*, *l*, and delivered through suitable wire conductors to the terminals *a*, *b*. The field-coils *s* are in the usual manner connected as a shunt, at the terminals. In addition to these main brushes *k* and *l* there are placed on the commutator other brushes, *k'* and *l'*, brush *k'* being in the same zone of commutation as brush *k*, and brush *l'* in the same zone as *l*; that is to say, the neutral line of the armature is a substantially horizontal line *o-n* across the center of the armature and commutator, between *k* and *k'* on one side and between *l* and *l'* on the other. The distance between brushes *k* and *k'* is small, and their position on the commutator is such that the armature coils in-

cluded between them are removed from the pole faces and cut only a small flux. The same is true of brushes *l* and *l'*.

Between the principal brush of positive sign, *k*, and the auxiliary brush of the same sign, *k'*, is interposed an auxiliary field-coil *i*, and likewise, between the main brush *l* and the auxiliary brush *l'* of negative sign, is interposed an auxiliary field-coil *i'*. The brushes may be of any suitable usual type, and mounted in the ordinary manner, which will be well understood without detailed description. Furthermore the number of principal and auxiliary brushes depends only upon the number of poles and the winding of the machine. Assuming that for the normal or mean value of current and voltage of a generator of the type described, turning at constant speed in the direction indicated by the arrow in Fig. 1, the neutral line is at equal distance from the two brushes of like polarity, then, as the current which may pass in the coils *i* and *i'* depends only on the value of the electromotive force between the brushes of like polarity, *k* and *k'* for coil *i*, and *l* and *l'* for coil *i'*, the electromotive force and current in *i* and *i'* is in this instance nothing. Assuming however that through a variation in the resistance the current increases. The neutral line will approach the position *o¹n¹*. An electromotive force will thereby be created between *l* and *l'* and between *k* and *k'* thus causing a current in the coils *i* and *i'*. This current will act to diminish the flux issued from the poles; the armature reaction helping; if the values of *i* and *i'* are properly determined, the flux will decrease and the voltage will decrease in the same ratio that the current increases, and the energy resulting therefore remains constant. If, on the contrary, the current had decreased, the neutral line would have moved in the opposite direction, respectively nearer *k'* and *l'*, the current in the coils *i* and *i'* would have been produced in the opposite direction and would have helped increase the flux in such manner as to increase the voltage in the same ratio that the current had decreased.

The novelty of our invention lies not merely in the auxiliary field-coils, but in the excitation of those coils by a current from a difference of potential occurring on opposite sides of the neutral line in a zone of commutation.

The armature being rotated, current is

generated in the coils of the same, and flows through the brushes k , k' , conductors 14 and 15, and coil i to the terminal a , and coil s to the terminal b . From the positive terminal a it is taken for use by any suitable conductor. The part of the current shunted through the field-coil s and returning at the terminal b completes its circuit through the machine, together with the main return 10 which also enters at the terminal b , through coil i' , conductors 16 and 17, and brushes l , l' .

As above stated, the main coils are mounted shunt with the armature winding. In certain circumstances it may be useful to 15 have a shunt machine working as a series machine, for instance when the circuit of a dynamo is suddenly closed on a very small resistance the machine would not be excited if it were only shunt, but ought to have 20 a strong series excitation; this may also be useful to gradually come back to the former excitation. For this purpose the following device is employed, the same being shown in Fig. 2. The additional field coils i , i' , are 25 constantly connected to one of the brushes (k or l for instance); the connection to the other corresponding brush may be cut off or suitable resistance may be thrown in. The line is, however, always directly connected 30 to the end a b of the coils i , i' , the resistance being also thrown in between the line and the corresponding additional brush. For example in Fig. 2 the coil i is always 35 connected to the brush k and to the line at a . The other brush k' is connected to a by variable resistance r' . These connections can also be completely cut out.

The operation of the device of Fig. 2 is as follows: When the switches c and c' are 40 opened, the entire current from the armature passes from k and l through i and the line. The coils i are series wound. When now k' and l' are connected to a and b by closing the switches, a part of the current of the 45 armature passes by i , the rest going to the line from k' and l' through the resistances. As the resistance decreases, that part of the current that passes through i decreases until, when the connection is made directly be-

tween k' and a , and between l' and b , the 50 conditions of Fig. 1 are approximated and the current passing through i depends only on the value of the electromotive force between the brushes in the same zone of commutation, as before described. 55

We claim:

1. In a dynamo electric machine, a field-winding producing a field of opposite poles, an armature intermediate said poles, a commutator, and a double set of brushes including a main set and an auxiliary set, each brush of the auxiliary set being in the same zone of commutation as one brush of the main set, said zones of commutation embracing the neutral points, the field winding 65 being composed of a prevailing shunt winding and an auxiliary winding having coils which connect respectively the positive main brush of one set with the positive auxiliary brush of the other set and the negative main brush of one set with the negative auxiliary brush of the other set. 70

2. In a dynamo electric machine, a field-winding producing a field of opposite poles, an armature intermediate said poles, a commutator, a double set of brushes including a main set and an auxiliary set, each brush of the auxiliary set being in the same zone of commutation as one brush of the main set, said zones of commutation embracing the 75 neutral points, the field winding being composed of a prevailing shunt winding and an auxiliary winding having coils which connect respectively the positive main brush of one set with the positive auxiliary brush of the other set and the negative main brush of one set with the negative auxiliary brush of the other set, and variable resistances in 80 said auxiliary windings. 85

In testimony whereof we have signed this 90 specification in the presence of two subscribing witnesses.

DIMITRY BALACHOWSKY.
PHILIPPE CAIRE.
